UNITED STATES PATENT OFFICE.

EMALINE T. ROSSO, OF COLUMBUS, OHIO.

DECORATED ELASTIC STRIP.

Application filed December 4, 1920. Serial No. 428,408.

To all whom it may concern:

Be it known that I, EMALINE T. Rosso, a citizen of the United States, residing at Columbus, in the county of Franklin and State of Ohio, have invented certain new and useful Improvements in Decorated Elastic Strips, of which the following is a specification.

This invention relates to improvements in 10 decorating elastic strips, and has for its object to provide a strip of this nature which may be ornamented or embellished by an application of beads or other analogous devices or articles, without minimizing or interfering with the normal elasticity of the 15 strip upon which the beading is applied.

For a further understanding of the invention, reference is to be had to the following description and to the accompanying 20 drawing, in which:

Figure 1 is an elevation of a section of elastic material decorated or finished in accordance with the present invention,

Figure 2 is a vertical transverse sectional view taken along the plane disclosed by the line 2—2 of Figure 1, and

Figure 3 is a similar view taken through a slightly modified form of the invention.

Referring more particularly to the details 30 of the invention, I take a section of elastic material 1 of any suitable nature, such for example as an elastic fabric, of the type which may be employed for very numerous purposes, one instance of which may be its 35 use in connection with wearing apparel or in various novelties.

It is desirable that such material should be decorated or otherwise rendered attractive for both commercial and aesthetic reasons, and to this end it has heretofore been customary to produce the elastic fabric in varying colors or tints or to embellish the same by means of embroidery and similar needle work. However, the present invention 45 aims to improve such ornamentation by applying glass or other beads to one or more of the exterior surfaces of the material, and in this manner to produce a novel and pleasing visual effect, which is believed to 50 be an improvement over the previous methods of decoration above outlined.

It is of course not within the province of this application to protect the application of beads or other similar devices to fabric 55 or other non-elastic materials, however, to

the best of my knowledge the application of beads or the like to an elastic material is thought to be new and to constitute an original idea. Heretofore, it has been considered impracticable to produce such an ornamental effect because of the manner of fastening the beads in position, which has usually resulted in diminishing or overcoming the elasticity of the material upon which they were applied. The present invention, therefore, consists in applying the beads to the elastic material without sacrificing in any way the elasticity of the material so embellished.

To this end, an exterior surface of the material 1 has placed thereon a plurality of parallel rows of beads or other similar devices 2, the fastening thereof being effected by passing threads 3 longitudinally through the eyes 4 of each of the rows of the beads, in such manner that each of the threads 3 will be independent of the others. In this instance the ends of said threads are suitably engaged or entwined through the fabric constituting the section 1, so that each row of 75 beads will be securely and positively fastened in connection with the elastic material, 80 upon which they are used. By this construction it will be observed that each row of 85 beads is independently fastened to the material 1, and accordingly the said material may be stretched in the usual manner to its maximum extent without in any way having the elasticity thereof diminished or destroyed by the beading. The same result can 90 be carried out by substituting, as shown in Figure 3, fine metallic wires 5 for the threads 3, or other equivalent methods may be employed for connecting the beads with the fabric 1 in accordance with the principles 95 of this invention.

From the foregoing description it will be apparent that the present invention provides a new and useful method and article of manufacture wherein elastic material of any 100 description may be attractively finished by beading for the purpose of rendering the material attractive and salable. In its final form the material so finished may be placed into many different uses, such, for example, 105 as wrist watch holders, belts or other similar garments or novelties. The beads may, of course, be of varying color and suitably patterned and matched to produce any desired 110 effect.

What is claimed is:

1. As a new article of manufacture, an elastic fabric strip having parallel rows of beads disposed transversely thereon, independent threads passing through the beads of each row, the ends of the threads being secured to the respective edges of the strip to hold the rows of beads in mutual contact with the strip, the strip and rows of beads being independently movable to preserve the normal elasticity of the strip.

2. An elastic fabric strip, a plurality of rows of beads arranged transversely of the strip, the beads of the rows lying in unattached relationship with respect to the strip to permit said strip to retain its normal elasticity, and threads passing through the beads of each row and secured at their ends to the strip, as and for the purpose set forth.

In testimony whereof I affix my signature.

Enialine T. ROSSO.
